UNITED STATES PATENT OFFICE.

JAMES F. HARRISON, OF ST. LOUIS, MISSOURI.

GARTER.

1,205,092.

Specification of Letters Patent.

Patented Nov. 14, 1916.

Application filed January 10, 1916. Serial No. 71,264.

To all whom it may concern:

Be it known that I, JAMES F. HARRISON, a citizen of the United States, residing at 3034 Easton avenue, in the city of St. Louis 5 and State of Missouri, have invented certain new and useful Improvements in Garters; and I do declare the following to be a full, clear, and exact description of the invention, such as will enable others skilled in the 10 art to which it appertains to make and use the same.

This invention relates to improvements in the construction of garment supporters, more especially to garters of the type 15 wherein a band of flexible or elastic material is designed to encircle the leg.

One of the objects of the present invention is to provide a device having an improved means for forming the garment attaching structure.

With the above and several other objects in view, my invention relates to the novel features of construction, combination and arrangement of parts which will hereinafter 25 be more particularly described and claimed and shown in the drawings wherein:

Figure 1 is a perspective view of a garter employing my improved details of construction; Fig. 2 is an enlarged vertical section 30 through the garment attaching means; Fig. 3 is a detail view showing the position assumed by the elastic band before it is tightened into operative engagement with the garment attaching member; Fig. 4 is a similar view showing said band tightened; Fig. 5 is an enlarged vertical longitudinal section on the line 5—5 of Fig. 4; Fig. 6 is a plan view of the button carrying member; Fig. 7 is a transverse section on the 35 line 7—7 of Fig. 6; and Fig. 8 is a plan view of the blank from which the button carrying member is formed.

The type of supporter illustrated in the accompanying drawing embodies broadly a 45 leg encircling band 1 preferably of elastic or flexible material, to which the garment attaching member 2 is secured. In the present invention this attaching member 2 is preferably formed of celluloid or similar 50 non-rusting material and comprises a slightly curved plate to which the attaching means proper is secured. One portion of the attaching means is formed integrally with the plate 2, in fact is merely a continuation of

said plate and has a keyhole slot 3 formed 55 therein as is common in devices of this character.

For coöperation with this keyhole slot I provide a button 4 carried by a suitable plate 5. In forming this button, I provide 60 the blank shown in the accompanying drawing which consists of the plate 5 having a tongue 6 extending therefrom, the intermediate portion of said tongue being enlarged as shown at 7 to form the head of 65 said button 4. When the blank has been stamped in the proper form, the tongue 6 is bent at the point of its connection with the plate 5 into a plane at right angles thereto, the enlarged portion 7 being then 70 bent over the plate 5 substantially parallel thereto. The remaining portion of the tongue which extends beyond the enlarged portion 7 is then bent downwardly at right angles to the plate and into engagement 75 therewith. The portions of the tongue on each side of the enlarged portion 7 form the neck of said button 4 and space said enlarged portion from the plate 5. This last-mentioned end of the tongue 6 is slightly 80 enlarged at its extremity as shown at 8, and when this is bent downwardly it engages a notch 9 formed in one wall of a slot 10 in the plate 5, said notch 9 having inclined end walls to receive and retain the enlarged portion 8. After the blank has been bent into 85 the above described shape, it is ready to be attached to the garment attaching member. This may be accomplished by any preferred means, that shown consisting in 90 passing a tape 11 through the slot 10 and through an additional slot 12 in the upper portion of the plate 2. This tape thus forms a tab for flexibly connecting said plate 5 with its button to the other portion of the 95 garment attaching means in position to engage said keyhole slot 3. A gripping ring 12 of yieldable material also preferably surrounds the button 4 to enable it to more securely hold the hose or other garment.

The plate 2 of the garment attaching member is provided in addition to the slot 12 with the slots 14 and 15 disposed substantially at right angles to said slot 12 and are adapted to receive the leg encircling band 1. 105 One end of the flexible or elastic band 1 is inserted through the slot 15 from the front to the rear face of the member and is then

passed across said rear face and inserted through the slot 14 in the same direction. The arrangement of the band before tightening the same is clearly shown in one of the 5 figures of the drawing. When the opposite end of the band is pulled tight, the portion thereof extending over the rear face of the plate 2 clamps the first-mentioned end between it and the said plate, thus holding the 10 band in adjusted position without the aid of stitching or other fastening means other than that described. It is obvious that by loosening the band and drawing on the proper portion, the length thereof may be increased or 15 decreased as desired. The free end of the flexible band 1 carries a suitable fastening member 17 which is adapted to be engaged with the plate 2 when the garter is to be disposed around the leg of the wearer. In the 20 rear view of the device, it will be readily noted that this leg encircling band and the tab 11 covers a considerable portion of the garment attaching member and allows very little of it to touch the wearer, and as all parts 25 of the device including the band and the tab are of a non-rusting material, the wearer will not be troubled by that part which comes in contact with his flesh.

Copies of this patent may be obtained for five cents each, by addressing the "Commissioner of Patents,
Washington, D. C."

I claim:—

In a device of the class described, a garment attaching member, a coöperating button carrying member comprising a plate having a slot, one wall of the slot being notched and having its end walls inclined, and a tongue extending from said plate and provided with an enlarged portion intermediate its ends, said portion forming the head of a button, said tongue being bent outwardly at right angles to the plate at the point of its connection therewith, the enlarged portion being then bent over the plate, the free end of the tongue beyond said enlarged portion being bent inwardly into contact with said plate, the extreme end of said tongue being slightly enlarged and engaged with said notched wall, and a tab extending through said slot and connected to the garment attaching member.

In testimony whereof I have hereunto set my hand in presence of two subscribing witnesses.

JAMES F. HARRISON.
